His Attorney.

UNITED STATES PATENT OFFICE.

HARRY J. SHELTON, OF ST. LOUIS, MISSOURI.

GRINDER AND SHREDDER.

1,307,761.

Specification of Letters Patent. Patented June 24, 1919.

Application filed February 1, 1919. Serial No. 274,536.

To all whom it may concern:

Be it known that I, HARRY J. SHELTON, residing in the city of St. Louis and the State of Missouri, have invented a new and useful Improvement in Grinders and Shredders, of which the following is a full, clear, and exact specification, reference being had to the accompanying drawings, which form a part thereof.

10 My invention relates to a machine that may be used for grinding free flowing material, such as peas, beans, or similar articles, or for shredding fibrous material, such as alfalfa, hay, pea vines, and similar substances.

The object of my invention is to provide a single machine which can be used for grinding free flowing material, such as peas, or which by a slight adjustment may be used for shredding fibrous material, such as alfalfa; and a further object of my invention is to provide a machine that is especially adapted to the needs of farmers, in that there will be combined in a single device, a grinder for free flowing material and a shredder for fibrous material.

My invention is fully shown in the accompanying drawing where Figure 1 is a vertical interior view partly in section, of 30 the machine when used as a shredder; Fig. 2 is a vertical interior view of a part of the machine when adapted to be used as a grinder; Fig. 3 is a section along the line 3—3 of Fig. 1; and Fig. 4 is a section along 35 the line 4—4 of Fig. 2.

Referring to the figures, A is a housing or casing having mounted inside of it a plurality of hammers B which are adapted to be made to rotate by means of the shaft C. 40 D is a grinding surface which occupies the greater part of the upper half of the casing, and E is a screen through which the ground or shredded material passes from the grinding chamber into the space below and from

45 which space it is withdrawn by any suitable means. F is a supply duct having walls K' and K and through which free flowing material, such as peas, beans, bran, etc., is supplied to the grinding chamber.

50 G is a feed mechanism by means of which fibrous material, such as pea vines, alfalfa, etc., are fed to the machine through the channel between the walls J and K when it is used as a shredder. H and I represent 55 belt conveyers in the feed mechanism G.

Inasmuch as the kind of feed mechanism used for supplying the fibrous material to the machine when it is used as a shredder does not form a part of my invention, I have not shown the feed mechanism complete, and I do not intend that my invention shall be restricted to use with a feed mechanism precisely like that shown in the drawing. An inlet opening is formed in the circumferential wall of the grinding chamber, and to this leads the supply duct for free flowing material and the channel from the feed mechanism for fibrous material. This inlet opening is, preferably, made so that its upper edge registers with the upper 70 wall K' of the supply duct and its lower edge registers with the lower wall J of the channel from the feed mechanism G. The supply duct and the channel from the feed mechanism G, preferably, have a common 75 wall K' which ends at the inlet opening substantially midway between the upper and lower edges thereof as shown.

L is a gate which is adjustably mounted in the inlet opening and forms a part of the 80 circumferential wall of the grinding chamber and which is of sufficient size to extend from the wall K to either the wall K' or the wall J so as to prevent, as may be desired, the passage of free flowing material or 85 fibrous material into the grinding chamber. The gate L is preferably provided with teeth M so that its inner surface forms a grinding surface, and it is arranged to slide in grooves P cut in the side walls of the housing A 90 between the end of the section of the grinding surface D and the end of the screen E. N is a set screw which passes through one side wall of the housing and which is adapted to hold the gate L in adjusted position. 95 The gate L is provided at one lower corner with a notch Q in which the screw N is adapted to enter when the gate is in the position shown in Figs. 1 and 3.

When the gate L is in raised position as 100 shown in Figs. 1 and 3 the supply duct F is cut off from the grinding chamber and material may be fed into the machine through the feed channel from the feed mechanism G, and the machine acts as a 105 shredder. When the gate is in lowered position, as shown in Figs. 2 and 4, communication between the feed mechanism G and the grinding chamber is closed and fibrous material cannot be fed to the machine, but 110

free flowing material may enter the machine from the supply duct F, and the machine acts as a grinder.

It is evident that the sizes of the various parts may be varied to suit the different conditions, and the means used for holding the gate L in raised position may be changed without departing from the spirit of my invention.

10 What I claim as new and desire to secure by Letters Patent, is:

1. A grinding and shredding machine having a housing containing a grinding chamber with revoluble hammers mounted therein, a grinding surface forming the upper circumferential wall of said chamber and made in two sections, one of said sections being fixed in position and the other of said sections being adjustable circumferentially, 15 20 25 a supply duct through which free flowing material may be fed into said chamber, a feed channel for fibrous material and means whereby said adjustable section may be positioned so as to prevent the passage of material into said chamber from said supply duct or from said channel as may be desired.

2. A grinding and shredding machine having a housing containing a grinding chamber with revoluble hammers mounted therein, a grinding surface having an inlet opening therethrough and a section of said surface adjustably mounted in said opening, a supply duct for free flowing material, a feed channel for fibrous material, said supply 30 35 duct and said feed channel both leading to said inlet opening and said adjustable section of said grinding surface being shiftable from one of the feed openings to the other.

3. A grinding and shredding machine having a housing containing a grinding chamber with revoluble hammers mounted therein, a screen forming the lower circumferential wall of said chamber, an imperforate grinding surface forming the upper circum-

ferential wall of said chamber and positioned so as to abut at one end against one end of said screen and leave an inlet opening between the non-abutting ends of said surface and said screen, an imperforate section of grinding surface adjustably mounted 50 in said opening, a supply duct for free flowing material, a feed channel for fibrous material, said supply duct and said feed channel both leading to said inlet opening and said adjustable section of grinding surface 55 being shiftable from one of the feed openings to the other.

4. A grinding and shredding machine comprising a housing having a chamber with revoluble hammers mounted therein, a screen forming the lower half of the circumferential wall of said chamber, an imperforate grinding surface forming the upper circumferential wall of said chamber and made in two sections, one of said sections being fixed in position and abutting at one end against one end of said screen and the other of said sections being adjustable circumferentially between said fixed section and said screen, a supply duct whereby free 60 65 70 75 80 85 flowing material may be fed into said chamber having one wall registering with the non-abutting end of said fixed section of said grinding surface, a feed channel for fibrous material having one wall registering with the non-abutting end of said screen, a wall common to said supply duct and said feed channel, and means whereby said adjustable section of said grinding surface may be held in position at either side of said common wall thereby preventing the feeding of material into said chamber at that side of said wall at which said section is positioned.

In witness whereof I have signed my name to this specification.

HARRY J. SHELTON.
